METALLIC RAILWAY TIE

Filed June 21, 1928

UNITED STATES PATENT OFFICE.

HENRY D. ROBINSON, OF SORRENTO, CALIFORNIA.

METALLIC RAILWAY TIE.

Application filed June 21, 1928. Serial No. 287,111.

This invention relates to a metallic railway tie, and has for one of its objects to provide a novel device of this character which will be light in weight and exceptionally strong and durable and capable of being manufactured and sold at a comparatively low cost.

With the foregoing and other objects in view, the nature of which will appear as the 10 description proceeds, the invention consists in the construction, combination and arrangement of parts hereinafter fully described and claimed, and illustrated in the accompanying drawing, wherein:

Figure 1 is a top plan view of the tie with the rails secured thereto, one of the rails being partly in horizontal section,

Figure 2 is a view in side elevation of the tie with the rails in vertical section,

Figure 3 is a sectional view taken on the vertical plane indicated by the line 3—3 of Figure 1,

Figure 4 is a sectional view taken on the vertical plane indicated by the line 4—4 of Figure 1,

Figure 5 is a sectional view taken on the vertical plane indicated by the line 5—5 of Figure 1, and

Figure 6 is a sectional view taken on the vertical plane indicated by the line 6—6 of Figure 1.

The tie comprises a metal casing 1 which is closed at its ends and provided with openings forming transverse recesses 2 and interior longitudinal webs 3. The recesses 2 extend through the top wall and through the upper portions of the side walls of the casing 1. The webs 3 extend from the top to the bottom wall of the casing 1, and are located centrally between the side walls of the casing. The webs 3 extend in opposite directions beyond the recesses 2, and are provided with recesses 4 which are arranged in alignment with the recesses 2. Flanges 5 extend downwardly from the side walls of the recesses 2 and from one side wall of the casing 1 to the other side wall thereof, and they contact with the bottom and end walls of the recesses 4. The tie may be cast or made from sheet metal. When made from sheet metal, the margins of the sheet metal blank will be welded together and the webs 3 will be welded to the top and bottom walls and flanges 5 of the casing 1.

Plates 6 and 7 are arranged in the recesses 2 and 4 and rest upon the side walls of the

casing 1 and upon the webs 3 to which parts they are welded. The plates 6 and 7 are positioned between the flanges 5 and welded to such parts. The plates 6 and 7 extend beyond the side walls of the casing 1, the former being provided with laterally extending lugs 8 contacting with the outer surfaces of said walls, and the latter being of uniform width throughout. Certain of the 60 lugs 8 are provided with bolt receiving openings 9, and the plate 7 is provided with bolt receiving openings 10, the openings 9 being elongated in the direction of the length of the casing 1 and the openings 10 being elongated in the direction of the width of the casing. Wooden blocks 11 and 12 are arranged in the recesses 2 and 4 upon the plates 6 and 7, and each block is similar in contour to the plate upon which it rests 65 and provided with openings corresponding to the openings 9 and 10, respectively. The blocks 11 and 12 provide elastic cushions or rests for the rails 13 and 14, the rail 13 being secured in place by clamps 15 and 70 bolts 16, and the rail 14 being secured in place by bolts 17. The clamps 15 contact with the base of the rail 13, and the bolts 17 pass through the base of the rail 14.

As the ends of the casing 1 are closed, and as the recesses 2 are closed by the flanges 5 and the plates 6 and 7, water cannot enter the tie. The webs 3 materially strengthen and reinforce the tie, and also support the plates 6 and 7 at their transverse centers. 80 By providing for adjusting the clamps 15 transversely of the track through the provision of the elongated openings 9 it will be apparent that adjustment of rail 13 relatively to rail 14 may be readily effected to 90 bring the rails to correct gauge due to wear or other cause. The slip engagement of the clamps 15 with rail 13 and movement of the bolts 17 in the slotted openings 10 admit of movement of the rails longitudinally in 100 expansion and contraction.

It should be understood that the drawing is merely illustrative and does not pretend to give exact proportions. Furthermore, the said drawing is illustrative of a preferred construction, it being my expectation that various changes and modifications may be made without departing from the spirit and scope of my invention.

What is claimed is:—

1. A tie comprising a casing closed at its ends and provided in its upper side with

openings forming transverse recesses, flanges extending downwardly from the top wall of the casing at the sides of the recesses and from one to the other side wall 5 of the casing, and plates arranged in the recesses upon the side walls and in contact with the flanges.

2. A tie comprising a casing closed at its ends and provided in its upper side with 10 openings forming transverse recesses, flanges extending downwardly from the top wall of the casing at the sides of the recesses and from one to the other side wall of the casing, plates arranged in the recesses upon the 15 side walls and in contact with the flanges, and webs arranged within the casing and extending longitudinally thereof, the webs being positioned centrally between the side walls of the casing and connected with the 20 top and bottom walls thereof and provided

with recesses for the reception of the plates and flanges.

3. A tie comprising a casing provided in its upper side with transverse recesses, plates arranged in the recesses and extending beyond the side walls of the casing, one of the plates being provided with transversely elongated and the other with longitudinally elongated bolt receiving openings, and cushion blocks arranged within the recesses upon 25 the plates. 30

4. A tie provided in its upper side with transverse recesses, and plates arranged within the recesses, one of the plates being provided with transversely elongated and 35 the other with longitudinally elongated bolt receiving recesses.

In testimony whereof I affix my signature.

HENRY D. ROBINSON.
